UNITED STATES PATENT OFFICE

DARIUS FARRINGTON GALLAGHER, OF BROOKLYN, NEW YORK.

VALVE-GEAR.

SPECIFICATION forming part of Letters Patent No. 376,082, dated January 10, 1888.

Application filed November 30, 1886. Serial No. 220,316. (No model.)

To all whom it may concern:

Be it known that I, DARIUS FARRINGTON GALLAGHER, of Brooklyn, Kings county, New York, have invented certain new and useful 5 Improvements in Valve - Gears for Steam-Engines; and I do hereby declare that the following is a full, clear, and exact description of the same, reference being had to the accompanying drawings, forming part of this specification.

My invention is applicable to all large steam-engines, whether stationary or marine; but it is, perhaps, more particularly applicable to marine engines of the compound type. It 15 makes use of small auxiliary steam-cylinders and pistons with valves for the introduction thereto and ejection therefrom of steam for actuating the auxiliary pistons, which are fixed directly or indirectly to the valve-stems 20 of the main valve and actuate the latter in such manner as to effect all the events of lead, full port-opening, cut-off, and exhaust-closure at the proper times to secure the best results, and the main valve thus actuated may perform 25 its service both for the high-pressure and low pressure cylinders of a compound engine. One of the small auxiliary steam-cylinders (with its piston and valve constituting a small auxiliary engine) has its valve connected with 30 any ordinary reversing valve-gear of a steam-engine, and such valve-gear may be made of a size and strength proportional only to the size of this small engine, and therefore it can be much more cheaply made and much more 35 easily manipulated than the valve-gear of the size ordinarily employed, while it effects all the necessary control of the main engine more effectively than the ordinary-sized valve-gear, no other than this small gear being needed 40 for the largest engine. This first auxiliary engine controls the opening of the valve, and for this purpose its piston is connected with a valve-stem of the main valve which plays through a stuffing-box at one end of the steam-chest. The second small auxiliary engine performs the cut-off at the proper instant in the 45 stroke, and for this purpose its piston is connected with a valve-stem of the main valve which plays through a stuffing-box at the end 50 of the steam-chest opposite that already named. The piston of the first small auxiliary engine is larger than that of the second small auxil-

iary engine, and one has the same stroke as the other. Steam is introduced to opposite sides of their respective pistons in such manner that the piston of the first auxiliary engine not only moves the main valve, but also overcomes the steam pressure exerted against the opposite side of the piston of the second auxiliary engine, and the valve of the first auxiliary engine, when moved into position for its exhaust by its valve-gear releasing the piston of this engine from pressure, the piston of the second auxiliary engine throws back the main valve into the position for its cut-off. The first auxiliary engine also has a cut-off movement of its valve effected by an independent cut-off gear, which is preferably a still smaller third auxiliary engine constructed and operating in a manner precisely analogous to the second auxiliary engine.

Having thus outlined the nature of my invention, I will proceed to describe the same in detail, referring now to the drawings, in which—

Figure 1 is a central vertical section through the high-pressure and low-pressure cylinders of a compound marine steam-engine and through the cylinders of the three auxiliary engines named, with side elevations of moving parts essential to this example of my improvements. Fig. 2 is a cross-section made through the high-pressure cylinder, low-pressure cylinder, and steam-chest of the same, the section being made on the line *x x* in Fig. 1. Fig. 3 is a partially-sectional side view of a piston-valve preferably used, but not essential to my improvement, and which may form the subject of a future application for Letters Patent. Fig. 4 is a plan view of said piston, illustrating details of its construction. Fig. 5 is a vertical central section through what I have herein styled the "first small auxiliary engine" and the "third auxiliary engine." Fig. 6 is a horizontal central cross-section through the cylinder and steam-chest of the same, made on the line *y y* in Fig. 5. Fig. 7 is a vertical section made through the steam-chest of the same on the line *z z* in Fig. 5. Figs. 8 and 9 are respectively top views of a detail of valve stem tripping-gear, which is a feature of my invention, and they show different positions, as well as the construction and operation of the parts of this feature of the in-

vention. Fig. 10 illustrates a part of the invention which relates to a variable cut-off, and the construction of which is a feature of my invention. Fig. 11 is a vertical central section through what I have herein styled the "second small auxiliary engine," illustrating not only its details and mode of operation, but also illustrating the construction and operation of the third small auxiliary engine, which is in all respects similar in form and operation to the second, differing from the latter only in size, position, and function. Fig. 12 is a section through the cylinder and steam-chest of the second small auxiliary engine, the section being made on the line *u u* in Fig. 11. Fig. 13 is a vertical section through the steam-chest of the second small auxiliary engine, the section being made on the line *v v* in Fig. 11.

Fig. 1 shows the parts in the position assumed at the first event of the stroke, both in the high-pressure and low-pressure cylinders—viz., the induction of steam to each. This position also corresponds with the period of the beginning of exhaust from both the high-pressure and low-pressure cylinders, the exhaust-steam from the high-pressure cylinder being inducted to the low-pressure cylinder in the usual manner and the exhaust from the low-pressure cylinder passing to a condenser, which, as it forms no part of my invention, is not represented in the drawings.

The high-pressure cylinder is lettered *E*, and the low-pressure cylinder *E'*.

The first small auxiliary engine is lettered *e*, the second *e'*, and the third *e''*.

There being nothing peculiar to my invention in the engines *E E'*, except the construction and arrangement of the steam chest and ports in relation with the cylinders and the main valve, and also the construction of this valve, it will be unnecessary to more than enumerate such parts of their construction as will make easy a complete explanation of the construction and operation of my improvements.

B and *B'* represent the pistons, respectively, of the high-pressure and the low-pressure cylinders; *CC'*, their piston-rods and connections. The piston-rods are shown as passing through the ordinary stuffing-boxes, and the pistons are of any approved construction.

D represents the steam-chest, and *A A' A''* the main valve, which latter will (except when necessary to distinguish some particular part of it) be referred to by the symbol *A*, &c. This valve is in this example of my invention of the piston variety, and this form is generally preferable for the purposes of my invention; but I do not therefore confine myself to this form, as some of the features of my invention upon which distinctive claims will hereinafter be made, and which will be hereinafter described, may, with easily-constructed modifications of other parts not embraced in the distinctive claims, be used with valves of other types. I therefore reserve the right to use, in combination with other parts of my

invention, any type of main valve which may be adapted to such use.

The main valve herewith shown has, however, some special features of construction, which I will proceed to describe. It is made up of four pistons, *A A' A'' A'''*, which are mounted upon a valve-stem, *F*. This valve-stem may be formed of one or more pieces, and the pistons *A A' A'' A'''* are arranged thereon with reference to the hereinafter-described steam-ports of the steam-chest *D* and the cylinders *E E'*.

The particular construction of the pistons of the piston-valve *A*, &c., is designed to afford means for adjusting their packing in such manner as to gain maximum tightness with minimum friction, and thus to insure their perfect action as regards a perfect balance of the steam-pressure upon them and the prevention of leakage. This construction is illustrated in Figs. 3 and 4, in which *a* represents the piston-head, *d* the follower, and *r r' r'' r'''* metallic expanding-rings. The rings *r r' r''* *r'''* may be made, however, of any composition or material suitable for the purpose. The inner ring, *r*, is of rectangular cross section, and is cut on one side or otherwise made to have on one side two inclined planes inclined toward each other approximately like the sides of the Roman letter "V," as shown in Fig. 3.

In the V-shaped space or opening formed by the inclined faces of the ends of the ring, as specified, is accurately fitted an expanding-wedge, *w*, Figs. 3 and 4, which, when forced into the V-shaped cut, space, or opening in the ring *r*, expands the latter to a larger diameter. When the wedge *w* is withdrawn or partially withdrawn out of said V-shaped opening ring *r*, through its own elasticity, contracts to a smaller diameter. In thus expanding or contracting it expands the superimposed rings *r' r'' r'''*, (which are also cut on one side, as shown, for *r'''* at *f''*, Fig. 4,) or permits them to contract also by the action of their own elasticity. The rings *r''* and *r'''* are preferably, but not essentially, dovetailed upon *r'*, as shown in Fig. 3, which assists in keeping them steam-tight and causes them to spring outward or inward as though they formed but a single ring, and at the same time permits their joints *f''* to be placed at different points of the circumference of the piston.

The expanding-wedge *w* is forced in either direction to effect the action described by turning a set-screw, *s*, which engages both the follower *d* and said wedge, and the latter is also held firmly in position by said screw when adjusted properly. The follower is held in position by a nut, *N*, Fig. 1; but in a series of such pistons—such as shown in Fig. 1—only one nut is needed for the series, the pressure of the nut being transmitted to all the followers but one by washers intermediate between the pistons *A A' A'' A'''*, as shown in Fig. 1, or by any other approved means. In this manner the respective pistons of the piston-valve are made to accurately fit their hollow cylin-

drical seats without leakage or undue friction, and so far as the steam pressure is concerned an accurate balance is secured.

The valve-stem F passes through suitable stuffing-boxes, S, out of both ends of the steam-chest D, the construction of the latter being in the present example of my improvement as follows: The high-pressure cylinder E has at each end a steam-port, p, for the induction and eduction of steam, and the steam-chest D has formed therein passages p', which are continuations of the ports p when said chest is bolted or otherwise attached to said high-pressure cylinder in due relation therewith, as shown in Fig. 1. The low-pressure cylinder E' also has at each end an induction and eduction port, p'', which, when acting as induction-ports, form continuations of the ports p' in the steam-chest D. Steam enters the chest D through the port p'', and when the valve A, &c., is in position, as shown, passes through the upper port, p' p, into the upper end of the high-pressure cylinder, as indicated by arrows. In the steam-chest are also formed ports p''', which, when the steam-chest is placed in proper relation with the low-pressure cylinder E', form continuations of the ports p''' for exhaust of steam from said cylinder, and when the valve A is in proper relation with either of said ports the flow of exhaust-steam takes place through such port, as indicated by arrows for the upper port in Fig. 1. After passing through either of the ports p''', the exhaust low steam enters one or other of the ports p⁵, which communicate with each other and with the final exhaust p⁶, by an extension or passage indicated by dotted outline in Fig. 1, and which is cored out in the side of the steam-chest. The arrangement of the pistons of the valve A, &c., is such that the high and low pressure steam-cylinders induct and exhaust their steam at similar piston positions; but I by no means limit myself to the precise arrangement of ports, &c., herein described, as it will be obvious no such limitation is necessary for the purposes of my invention.

It remains to describe the means employed for actuating the valve A, &c., wherein, together with the construction of the piston-valve A, &c., the essential features of the invention are comprised.

The lower part of the valve-stem F either forms or is connected with the piston rod of the first auxiliary engine, e, Figs. 1 and 5. In this example of the invention said valve-stem and piston-rod are identical. The valve A, &c., therefore moves with and is moved by the piston b of the engine e through the intervention of said valve-stem. Now, there is nothing substantially different in this example of my invention in the construction of the engine e and its D slide-valve from that of ordinary piston and slide-valve engines, except in the means for actuating its valve. I need, therefore, only describe this valve-gear. The valve-

stem f passes through suitable stuffing-boxes—one at each end of the steam-chest d'. The upper extremity of the valve-stem f has formed thereon or attached thereto a cylindrical boss, g, in the middle part of which is turned or otherwise formed an annular recess, h, (indicated in dotted outline in Fig. 5,) for the engagement of the spring-clip shown in Figs. 1, 5, 8, and 9, at G. This spring-clip G is composed of two parts or counterparts, i i', Fig. 5, with a compass joint, of which joint the slide-bar H, Figs. 1 and 5, forms the pivot. Springs k and k' are attached to the parts i and i', one spring to each part, the spring attached to each part engaging its counterpart in such manner that when pivoted upon the slide-bar H the free ends of the counterparts are forced toward each other by the action of the springs, and in such manner that the clip embraces and engages the aforementioned boss g upon the valve stem f, except when the parts i and i' are forced asunder, as hereinafter set forth.

The slide bar H is given reciprocating motion from an eccentric on the main shaft of the engines E and E', or by any other suitable mechanism for effecting such motion at the proper intervals synchronously with the movements of the pistons in said engines.

When the clip G is engaged with the boss g, the reciprocating motion of the slide-bar H moves, through the medium of the valve-stem f, the slide-valve K of the engine e, the construction of this valve and the direction both of inflow and outflow of steam controlled by it being the same as in ordinary slide-valve engines, the steam being admitted to the steam-chest through the port p' and exhausting through the port p⁸, Fig. 5. The opposite end of the main valve-stem F, extending through a stuffing-box, S, as already described, forms the piston-rod of the engine e', Figs. 1 and 11.

The valve of the engine e' is shown at K' in Figs. 1 and 11. In this example of my invention it is a simple D slide-valve; but it admits and exhausts steam in a manner opposed to that in which these functions are performed in an ordinary steam-engine—that is to say, steam is admitted to the steam-chest through the port p⁹ and exhausts through the port p¹⁰. Its valve-stem f' is, by means of an arm, L, rigidly attached to the valve-stem F, which is also the piston-rod of the engine e', and consequently the valve K' moves in the same direction as the piston b' of this engine and has the same stroke as the piston b' and the same length of stroke as that of the main valve A, &c.

The piston b of the engine e is made large enough not only to lift the valve A, &c., but also to overcome the pressure of the steam against the piston b' of the engine e', which pressure, as will be seen, acts in a direction opposed to that exerted by the steam against the piston b of the engine e. The result of this arrangement is that when the valve K of

the engine e is moved into the position of exhaust by the action of the engine e'' , as hereinafter explained, and the steam exhausts from the cylinder of the engine e , the pressure in the engine e' , acting against the piston b' , immediately moves the main valve A , &c., in the contrary direction from that in which it has just previously been moved by piston b of the engine e and cuts off the steam from both the high and low pressure cylinders $E E'$. At the same time the exhaust of the high-pressure cylinder is closed, as is usual with compound engines in which the induction and excretion of steam from both cylinders is controlled by a single valve-gear, and the exhaust of the low-pressure cylinder is also closed, this event thus taking place so early in the stroke as to give a higher degree of compression than is usually attained in this type of engine. An important advantage is thus secured—to wit, the thumping in passing the centers (one of the serious disadvantages of compound engines as hitherto constructed and operated) is entirely removed, this being one of the principal objects sought in my invention.

It will now be obvious that the parts of the invention will act precisely as described, no matter what means may be employed to operate the valve of the small auxiliary engine e , and that the period of opening the exhaust in said engine e will control the period in the stroke of the main pistons $B B'$ at which the cut-off and exhaust-closure will take place in the high and low pressure engines $E E'$. The parts so far described are therefore not dependent upon any special valve-gear for the small auxiliary engine e , any gear that will effect the proper movement of the valve K being sufficient to bring about in proper order all the essential movements of the main valve A , &c. Nevertheless, I have found the particular valve-gear hereinafter described, and which forms a part of my present invention, to be peculiarly advantageous, and I shall now proceed to describe the same.

The construction and operation of the engine e'' , Figs. 1 and 5, is in all respects substantially the same as the operation and construction of the engine e' . Its function is to perform the opening of the exhaust of the engine e when the high and low pressure pistons $B B'$ have reached the positions in their strokes at which it is desired to effect the events of cut-off and exhaust-closure for the engines $E E'$.

In the drawings, b'' represents its piston; K'' , its valve; f'' , its valve-stem, and L' the arm which rigidly connects the valve stem f'' with the piston-rod f . The valve K'' admits its steam and exhausts in the same manner as that described for the valve of the engine e' —that is to say, it takes steam through what is usually the exhaust-port of an ordinary steam-engine, and exhausts into and through what is ordinarily the steam-chest and what is ordinarily the inlet thereto, but which latter is here an outlet for exhaust-steam.

When the valve-stem f of the valve K (which valve-stem is also the piston-rod of the piston b'') is released from its engagement with the spring-clip G , hereinbefore described, the piston b'' , which has been moved against steam-pressure in the same direction as the valve K has been moved, is immediately moved in the opposite direction by the action of the steam-pressure. In thus moving, the piston b'' also moves the valve K into the position which allows the steam to exhaust from the cylinder e . The piston b' of the engine e' then assumes control of the main valve A , &c., and at once sets this valve back to its position of cut-off, as hereinbefore described. When it has thus set back the main valve to the position of cut-off, the piston b' stands at mid-stroke in cylinder e' , and is held there by equal pressure on both sides of said piston, the valve K' being then moved to its middle position, as shown in Fig. 11, and having inside lead. Both the steam-ports of said cylinder are therefore in communication with the passage p^o , which, as has been explained, is in this case a steam-port instead of an exhaust-port, as it would be in an ordinary steam-engine. This admits steam through the inlet p^o to both sides of the piston b' , balancing the pressure on said piston, and therefore leaving it free to move either way as it is next impelled by the piston b of the engine e , which, as has been explained, is also attached to the piston-rod F , common to both said pistons. If, by virtue of the momentum of their attached parts, the piston b' and its rigidly-correlated valve K' be moved so far as to release or partially release the pressure on either side of said piston, the pressure on the opposite side instantly forces them back to mid-position and holds them there until the piston b assumes control of the piston b' .

The movements to effect the cut-off after the main valve A , &c., has been moved into the position for full opening of the steam-ports in the high and low pressure cylinders $E E'$ are as follows: First, the release of the valve-stem f from its engagement with the spring-clip G ; second, the movement of the valve K of the engine e into the position for exhausting steam from said engine through the action of the piston b'' of the engine e'' ; third, the movement of the main valve A , &c., into its cut-off position and the simultaneous movement in the same direction of the piston b , effected through the action of the piston b' of the engine e' .

It remains only to describe the means for effecting the engagement and disengagement of the valve-stem f with and from the spring-clip G , and the means whereby the disengagement can be effected at any desired positions in their strokes of the pistons of the high and low pressure cylinders $E E'$. The parts or jaws $i i'$ of the spring-clip are formed with semi-cylindrical recesses $t t'$, Figs. 8 and 9, and when the jaws or counterparts $i i'$ are closed together, as in Fig. 9, these recesses form cylindrical holes or openings through the closed jaws, beveled out,

as shown in Fig. 10. The size of the opening t' is made to correspond with the diameter of the recessed part h of the boss g of the valve-stem f , Fig. 5, and when closed, as in Fig. 9, 5 said jaws, by their outer surfaces adjacent to the opening t' , engage firmly the shoulders of the annular recess h in said boss. When the parts i are opened into the position shown in Fig. 8, the valve-stem f is released from the 10 control of the spring-clip G and comes under the control of the engine e'' , which immediately sets the valve K back into its position for exhaust of steam from the engine e , which leaves the main valve A , &c., under the control 15 of the engine e' . The latter then at once moves the main valve into its cut-off position, as hereinbefore described. Such release of the valve-stem f from the control of the spring-clip G is effected by the rod m , Figs. 1, 5, and 20 10, and certain attachments, hereinafter described. By means of a collar, o , and nut q , the rod m is rigidly attached to and made to move with a slide, V , which slide is given a reciprocating motion by the cut-off eccentric 25 attached to the main engine-shaft, or by any other suitable mechanism in proper relation with the rotary motion of said shaft to effect the release of the valve-stem f at the proper periods in the strokes of the pistons of the 30 engines E and E' .

Right and left screw-threads are cut on the rod m at opposite positions on said rod, as shown at t'' , Figs. 5 and 10. To the screw-threads t'' are fitted female-threaded slides w' , 35 the inner extremities of which are formed into oppositely-inclined tapered surfaces, as shown in Figs. 5 and 10, at s' . By means of a band-wheel, w , the rod m may be turned on its longitudinal axis to bring the tapered ends of 40 the slides w' nearer together, or adjust them to a greater distance from each other, and the entering of the tapered end of one or other of said slides at each stroke or movement of the slide V wedges the parts i of the spring-clip G asunder and releases the valve-stem f at a point of the stroke of the pistons of the engines E and E' regulated by the adjustment of the slides w' . The outer part of the boss g then keeps the clip-jaws asunder, said boss 45 being of such length that the jaws i never slide off at either end, and when the reverse stroke of the slide V has brought the slides w' into the position shown in Fig. 5, and the reciprocation of the slide H has brought the clip 50 G into central relation with the recess h in the boss g , the clip is made to re-engage said boss by the action of the springs k .

The action of the entire gear may therefore be summarized as follows: The slide H first 55 moves, carrying with it the spring-clip G , the valve-stem f , and valve K , bringing the latter into position for the induction of steam to the cylinder e , and also moving the piston b'' and valve K'' of the engine e'' in the same direction, the piston b'' moving against pressure 60 of steam previously inducted to e'' . Next,

while the slide H is still moving in the same direction the piston b of the engine e moves under the pressure of the steam inducted by the valve K , said piston carrying with it the 70 valve-stem F , the valve A , &c., the valve K' and the piston b' of the engine e' moving the latter against the pressure of steam previously inducted to it, and also moving the valves A , &c., into the successive positions of lead and 75 full port-opening for the engines E and E' . Next, the movement of the slide V , which follows the movement of the slide H and is effected by independent mechanism, as hereinbefore specified, brings the tapered end of one 80 of the adjustable slides w' into engagement with the opening t in the spring-clip G and disengages the latter from the valve-stem f . Then the piston b'' of the engine e'' immediately moves the valve K of the engine e into 85 position for its exhaust, which leaving the piston b and valve A , &c., under control of the piston b' of the engine e' , the latter at once moves the valve A , &c., back into the position for its cut-off and exhaust-closure. In the next 90 succeeding stroke the same parts are moved in the same order, but in the opposite direction.

What I claim is—

1. The combination, with the main valve of a steam-engine and its valve-stem, of a first 95 auxiliary engine for moving said valve successively into the positions for effecting lead and full port-opening, a second auxiliary engine for effecting the movement of said valve into the positions for cut-off and exhaust-closure, (the piston of said second auxiliary engine and its valve being rigidly connected with the piston of the first auxiliary engine for effecting simultaneous movement in the parts so connected,) and mechanism for effecting the movement of the valve of the first auxiliary engine synchronously with the movement of the main shaft of the principal engine, substantially as and for the purposes described. 105

2. The combination, with the main valve of a steam-engine and its valve-stem, of a first auxiliary engine for moving said valve successively into the positions for effecting lead and full port-opening, a second auxiliary engine for effecting the movement of said valve into positions for cut-off and exhaust-closure, the piston of the second auxiliary engine and its valve being rigidly connected with the piston of the first auxiliary, means for effecting the induction of steam to the first auxiliary engine synchronously with the movement of the main or crank shaft of the engine, and a third auxiliary engine, the piston and valve of which are rigidly connected with the valve 115 of the first auxiliary engine for moving the latter into position for exhausting steam from said first auxiliary engine, substantially as and for the purpose set forth. 120

3. The tripping gear consisting of the spring-clip G , attached to and moving with the sliding bar H , the rod m , actuated by the slide 130

V, and the adjustable female-screw-threaded slides w' , fitted to right and left screw-threads on the rod m , all constructed and operating substantially as specified.

5 4. The combination of the main valve A, &c., the auxiliary engines $e e' e''$, the sliding bar H, tripping-gear for engaging the valve-stem of the valve of the engine e with and disengaging said valve-stem from said sliding

bar, and means for actuating said sliding bar to synchronously with the main or crank shaft of the principal engine, all constructed and operating substantially as and for the purpose specified.

DARIUS FARRINGTON GALLAGHER.
